E. N. LIGHTFOOT,
ELECTRIC HEATER,
APPLICATION FILED APR. 9, 1920.

1,403,330.

Patented Jan. 10, 1922.

UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

ELECTRIC HEATER.

1,403,330.

Specification of Letters Patent. Patented Jan. 10, 1922.

Application filed April 9, 1920. Serial No. 372,615.

To all whom it may concern:

Be it known that I, EDWIN N. LIGHTFOOT, a citizen of the United States, residing at New York, in the county of Bronx and State 5 of New York, have invented new and useful Improvements in an Electric Heater, of which the following is a specification.

This invention relates to an electric heater.

This electric heater is particularly useful 10 in press blocks of printing presses, although not limited to such use.

An object of this invention is to provide a simple, durable and efficient press block heater.

15 Another object is to provide an improved press block heater, the heating effect of which may be easily and quickly varied.

Another object is to provide an improved 20 heater wherein the possibility of damaging the heater when subjected to pressures of considerable magnitude is reduced.

Another object is to provide an improved 25 press block heater having a plurality of heating units which may be inter-connected in various combinations to obtain the desired heating effect.

Other objects and advantages will appear from the following description.

An embodiment of the invention is illustrated 30 in the accompanying drawings, wherein

Figure 1 is a top plan of the press block heater with the top or cover plate removed;

Fig. 2 is a vertical transverse section on 35 line 2—2 of Fig. 1;

Fig. 3 is a vertical transverse section on line 3—3 of Fig. 1;

Fig. 4 is a sectional view through one of 40 the heater units on line 4—4 of Fig. 1; and

Fig. 5 is a perspective of the press block heater.

The press block heater has a bottom plate 10, provided with a plurality of channels or pockets 11, for the reception of the heater 45 units 12, 13 and 14. These channels or pockets 11 communicate with a transverse channel or pocket 15, which contains conducting strips connecting the terminals of the heater units with the terminals of the heater. A

50 top or cover plate 16 may be suitably secured to the bottom plate 10 by screws 17, which are counter sunk, so that they do not project above the surface of the cover plate 16.

Each heater unit is made up of two flat 55 heaters 12^a and 12^b, etc. Each flat heater

comprises a resistor 18 in the form of a ribbon wound on an insulating core 19. The resistors of the two flat heaters of the units are connected in series by a resistor strip 20, or the resistors for each unit may be continuous. The two flat heaters of the unit are enclosed in an armor of two plates 25 and 26, the latter having flanges folded over the former. Insulating strips 27 and 28 separate the resistor ribbons from the armor plates 25 and 26. 60

The heater is provided with three plug terminals 30, 31 and 32, carried by an insulating strip 33, and extending through openings in a supporting bracket 34. Insulating 70 bushings are interposed between the terminal plugs and the edges of the openings in the bracket 34. The supporting bracket 34 is suitably secured to the front of the bottom plate 10 by screws 35. 75

One terminal of each heater unit is connected to a common conducting strip 36, which is in turn connected to the plug terminal 30 by means of a conducting strip 37. The other terminal of the heater units 12 80 and 14 are connected to a common conducting strip 38, which is in turn connected to the plug terminal 31 by means of a strip 39. The other terminal of the heater unit 13 is connected to the plug terminal 32 by means 85 of a conducting strip 40. These conducting strips are suitably insulated from each other and from the bottom and top plates by means of insulating strips 41, 42, 43 and 44. The conducting strips 37, 39 and 40 connected to 90 the plug terminals extend through a slot in the front of the bottom plate 10, and are insulated therefrom by an insulating strip 45, and from the top plate by an insulating strip 46. 95

The heater may be connected with the source of current supply by means of a three contact socket 50, to which is connected a three conductor cord or cable 51. This three conductor cord or cable may be connected 100 with three terminals of a five terminal control switch (not shown), to the other two terminals of which is connected the source of current supply.

The heater units 12 and 14 are connected 105 in parallel between plug terminals 30 and 31, while heater unit 13 is connected between plug terminals 30 and 32. By arranging the heating units in this manner three degrees of heat may be obtained from this 110

heater. To obtain the high degree of heat, all three heating units are in service, units 12 and 14 being connected in parallel relation and in series with unit 13. The medium degree of heat is obtained by employing units 12 and 14 connected in parallel, while to obtain the low degree of heat, heating unit 13 only is employed.

A control switch of any well known type 10 connected in circuit with the cable 51 and the source of current supply may be employed to switch the heating units into different arrangements whereby any one of the three degrees of heat are obtained from 15 this heater.

The construction of this heater is such 20 that it is very compact and thin, yet the resistor or heating elements thereof are thoroughly insulated. Thus there is produced 25 a highly efficient electric heater which is so thin that it may be employed in very shallow spaces. For example, this heater may be very efficiently used in press blocks associated with the embossing plates employed 30 in printing presses for embossing paper, cards, etc. Such press blocks are usually limited in thickness to about six hundred and twenty-five thousandths (.625) of an inch, and the heaters are mounted inside the 35 press block.

The described heater is of very rugged 40 construction, so that the heater will stand up under severe operating conditions, such as pressures of considerable magnitude. The 45 terminals are supported by a bracket provided on one edge of the heater and extend outwardly therefrom whereby the possibility of injuring the terminals is reduced.

The invention contained herein is, of 50 course, susceptible of other embodiments and adaptations.

What is claimed is:

1. An electric heater comprising a flat plate having a plurality of channels commu-

nicating with a channel common thereto, 45 a resistance element in each of the plurality of channels, terminals for the heater supported by the plate, conductors positioned in the common channel and connecting the resistance elements to the terminals, and a 50 cover for the channels.

2. An electric heater comprising a flat plate having a plurality of channels communicating with a channel common thereto, a 55 resistance element in each of the plurality of channels, a bracket secured to the plate and lying in the plane thereof, terminals for the heater supported by the bracket, and conductors positioned in the common channel and connecting the resistance elements to 60 the terminals.

3. An electric heater comprising a flat plate having a channel therein, a resistance element in said channel, a bracket secured to one edge of the plate and lying in the 65 plane of the plate, and terminals for the heater connected to the resistance element and supported by the bracket in the plane of the plate.

4. An electric heater comprising a flat 70 plate having a plurality of channels therein, a plurality of resistors in each channel, the resistors of the several channels being connected in various combinations, and terminals connected to the resistors and supported 75 by the plate in the plane thereof.

5. An electric heater comprising a flat plate having a plurality of channels therein, a 80 resistance element in each channel, a bracket secured to the plate and lying in the plane thereof, terminals connected to the resistance elements and supported in the plane of the plate by the bracket, and a cover for the channels.

In witness whereof I have hereunto sub- 85 scribed my name.

EDWIN N. LIGHTFOOT.
